UNITED STATES PATENT OFFICE.

EDMUND MARRISON BLAKE AND WILLIAM TIPLER, OF SYDENHAM, CHRISTCHURCH,
NEW ZEALAND.

TURNING-INDICATOR FOR VEHICLES.

1,280,952.

Specification of Letters Patent.

Patented Oct. 8, 1918.

Application filed October 30, 1915. Serial No. 58,909.

To all whom it may concern:

Be it known that we, EDMUND MARRISON BLAKE and WILLIAM TIPLER, subjects of the King of Great Britain; residing at 58 Falsgrave street, Sydenham, Christchurch, New Zealand, and 26 Talfourd street, Sydenham, Christchurch, New Zealand, respectively, have invented new and useful Improvements in Turning-Indicators for Vehicles, of which the following is a specification.

This invention relates to a device for use upon motor cars and other vehicles whereby the driver may give timely warning of his intention to turn such vehicle.

Hitherto it has been the practice for the driver to give this warning by extending his hand upon the side to which he is about to turn. This method is, however, in many cases, inconvenient and unsatisfactory inasmuch as it frequently involves the use of the hand required at that moment for manipulating the controlling mechanism of the car.

It is the object of the present invention therefore to provide a special device adapted to be brought into operation so as to display the desired signal, by means of a movement of the hand or limbs of the driver.

In carrying this object into effect the invention consists essentially of a rod, either solid or tubular, adapted to slide telescopically within a tube or casing mounted at a suitable position upon the car. Upon the extremity of the said rod is carried a disk, hand, or other means of giving the signal, such means being clearly visible from the side of the car when the rod is in the outward position. Suitable means are provided to enable the said rod to be conveniently controlled by the driver and such rod is provided also with suitable illuminating means adapted to come into operation when the rod is extended at night and so render the signal clearly visible.

In order that the nature of the invention may be clearly understood, reference will now be made to the accompanying sheet of drawings in which:

Figure 1.— is a rear view of the scuttle-dash of a car, showing one of the devices mounted thereon, the inward position of the

rod being shown in full lines, while its outward or extended position is indicated in dotted lines.

Fig. 2.— is a longitudinal section through one form of the device, illustrating the internal arrangement.

Fig. 3.— is a similar view to Fig. 2, showing an alternative construction therefor, and,

Fig. 4.— is an external view of the construction of Fig. 3 at right angles therewith.

The said construction comprises an outer tube 1 or casing 1 of any suitable form and adapted to be mounted at any desired position, such as upon the scuttle-dash 2 of, the car, as shown in Fig. 1.

Arranged within the casing 1 is a rod 3 either solid or tubular and which is adapted to slide telescopically in the said casing 1. For this purpose the rod 3 is provided at its inner end with a collar or flange 4 adapted to slide within the bore of the casing 1, while the latter is provided at or near its outer end with a bushing 5 through which the said rod 3 is adapted to slide.

Upon the outer or projecting end of the rod 3 is carried a suitable sign 6 by means of which the warning or signal is displayed when the rod 3 is in the outward or extended position, as indicated in dotted lines Fig. 1. This sign may be of any desired form, as for instance, an arrow-head as here shown, a disk, a hand and so forth.

In order that the signal may be discernible at night, means are provided for illuminating the sign 6 when the rod 3 is in the outward or extended position. For this purpose, an electric lamp 7 is provided in the outer end of the rod 3. The necessary supply of current for the lamp 7 may be obtained from any suitable or convenient source, such as the ordinary electric installation should the car be so equipped, or a battery 8 provided for the purpose, as shown in Fig. 2.

If so desired, in order to provide a self-contained device, an ordinary dry battery 9 may be arranged within the rod 3, as shown in Figs. 3 and 4. In this case one terminal

10 of the battery may be in permanent contact with one terminal of the lamp 7 while the other terminal 11 of the battery may be "earthered" to the metal of the device by means of a spring or plunger 12 interposed between such terminal and a cap or plug 13 upon the inner end of the rod 3. The said spring 12 serves also as a means of securing the battery 9 in place and keeping the 10 terminal 10 in contact with the lamp.

In all cases the arrangement is such that the lamp-circuit will be automatically closed by the rod 3 when in the outward position. For this purpose an insulated contact 14 is 15 provided upon the rod 3 at the required position and connected with the remaining lamp terminal in each case by means of an insulated lead 15, while at the required position upon the case 1 is arranged also an insulated terminal 16 with which the said contact 14 is adapted to make electrical connection when the rod 3 is in the outward position.

The said terminal 16 is connected, as by 25 means of a wire 17, with the remaining terminal of the battery or electrical source 8 or 9 as the case may be. In order to avoid an unnecessary waste of current as would be occasioned by allowing the lamp to light 30 each time the device were used in daylight, a switch 18 is preferably inserted in the lead 17 for the purpose of opening or closing the circuit as required.

For the purpose of operating the said 35 rod 3 so as to cause it to perform its said telescopic movement, any suitable means may be employed. Thus for example, as shown in Fig. 2, a rack 20 is provided or formed upon the rod 3 and with which rack 40 is adapted to intermesh a pinion 21 rotatably mounted within the case 1. The said pinion is provided with a suitable clock-spring which tends to turn the pinion in such direction as to carry the rod 3 into the outward 45 position, while to restrain the pinion against this tendency of the spring, such pinion is provided with a ratchet-wheel 22 with which it is adapted to engage a pawl or detent 23. By this arrangement, to cause the signal to 50 be displayed, the driver releases the pawl 23 from engagement with the ratchet-wheel, whereupon the pinion being free to rotate under action of its said spring, will carry the rod 3 into the outward position. To 55 enable the rod to be conveniently restored to its original position again, a knob or handle 24 is provided upon the said pinion or its spindle and adapted to be grasped by the fingers for the purpose of turning such 60 pinion against the tendency of the spring.

In the form shown in Figs. 3 and 4, the rack and pinion are dispensed with and a spiral spring 25 is interposed between the inner end of the case 1 and the rod. The

tendency of this spring 25, like that of the 65 previously mentioned form, is to carry the rod 3 into the outward position. To restrain the rod against this tendency, such rod is provided with an arm or handle 26 adapted to project outwardly through a longitudinal 70 slot 27 in the case 1, the inner end of such slot 27 terminating in a transverse slot or notch 28 within which the handle 26 is adapted to be engaged for the purpose of retaining the rod 3 in the inward position. 75 By this arrangement, to cause the signal to be displayed, the handle 26 is simply disengaged from the notch 28, thus permitting the rod 3 to move outward under action of its spring 25.

It will be obvious however that this operation of the rod 3 may be performed by various means such as for instance by the use of a Bowden-wire or other well-known intermediate devices adapted to be operated by a movement of the hand, foot, or limbs of the driver. The invention is not therefore to be limited to any of the above-mentioned means of operating but includes within its scope the employment of a rod bearing the 85 required sign and adapted to be operated telescopically within a casing by any suitable means.

In practice to enable a signal to be given on either side of the car according to the 90 direction in which the turning is to take place, the construction will be duplicated, that is to say two such devices will be employed and arranged one on either side of the car.

We claim:—

1. An indicator of the class described comprising a casing adapted to be mounted upon a suitable part of a vehicle, a rod mounted to slide telescopically in the said casing, a sign carried by the rod and adapted to be displayed from the vehicle when the rod is in its extended, operative position, means tending normally to project the rod into operative position, a toothed rack provided on the said rod, a pinion journaled in the casing in mesh with the rack, a ratchet carried by the pinion, and a manually operable releasing pawl engaged with the said ratchet and adapted normally to secure the rod in inoperative position.

2. An indicator of the class described comprising a casing adapted to be mounted upon a suitable part of a vehicle, a rod mounted to slide telescopically in the said casing, a sign carried by the rod and adapted to be displayed from the vehicle when the rod is in its extended, operative position, a toothed rack provided on the said rod, a pinion journaled in the casing in mesh with the rack, a coil spring connecting the said pinion with the casing and tending nor-

normally to project the rod into operative position, a ratchet carried by the pinion, and a manually operable releasing pawl engaged with the said ratchet and adapted normally to secure the rod in inoperative position against the tension of the spring.

In testimony whereof we have signed our

names to this specification in the presence of two subscribing witnesses.

EDMUND MARRISON BLAKE.
WILLIAM TIPLER.
